UNITED STATES PATENT OFFICE.

GEORGE AMBORN, OF CHAPINVILLE, CONNECTICUT.

LATHE-TOOL.

Specification of Letters Patent.

Patented Sept. 29, 1914.

1,112,185.

Application filed January 25, 1913. Serial No. 744,131.

To all whom it may concern:

Be it known that I, GEORGE AMBORN, a citizen of the United States, residing in Chapinville, in the county of Litchfield and State of Connecticut, have invented certain new and useful Improvements in Lathe-Tools, of which the following is a specification.

This invention relates to lathe tools and 10 aims to provide certain improvements therein.

The invention is particularly directed to an improved construction of what are known as cutting-off tool holders, being also 15 applicable to holders for side tools. This type of holder is provided with a shallow groove running longitudinally of the holder, the lower side of the groove being undercut to form a support for the tool, the latter being usually beveled along its lower edge 20 to fit the undercut portion. In such tools it is important that the holder shall not project beyond the side of the tool to any material extent as it would otherwise interfere with the operation of the tool in practice. The lower edge of the tool is held 25 against sidewise movement out of the groove by the undercut portion just referred to, and the upper edge is usually engaged by 30 a clamp which has a lip projecting over the upper edge of the tool, thus not only clamping the tool in place, but also preventing sidewise movement of its upper edge.

The present invention relates to an improved construction whereby the operations 35 of clamping and unclamping the tool are facilitated while at the same time the tool is firmly held in place in the groove, both its upper and lower edges being supported 40 against sidewise movement. To this end in place of the usual clamp I provide a cam member which extends through the tool holder and which is provided with a circular bearing face within the latter, the 45 end of the cam being projected beyond and over the tool receiving groove and being adapted to clamp the tool against the undercut edge of the groove. The cam face of such projecting end is also formed with 50 undercut edges so that in addition to clamping the tool in the groove, the cam acts to prevent the upper edge of the tool from being displaced sidewise out of the groove.

Referring to the drawings which illustrate one form of the invention,—Figure 1 55 is a side elevation of the holder and tool.

Fig. 2 is a top or plan view. Fig. 3 is a sectional view taken on the line 3—3 in Fig. 1. Fig. 4 is a section taken on the line 4—4 in Fig. 1.

Referring to the drawings, let A designate a tool holder of the type referred to which is provided in its side with a wide shallow groove B, the lower edge of which is undercut at C as best seen in Fig. 3. The tool 60 which is indicated by the letter D is generally flat in shape and is formed on its lower edge with a bevel E which is adapted to fit the undercut wall C of the holder. It is also formed on its upper edge with a similar bevel as shown at F by means of which it is adapted to be clamped in varying positions in the holder. The holder may be provided if desired with an undercut edge at the top of the groove B although in the present construction this is not necessary since the tool is adequately held by the cam to be referred to without the necessity of an interlocking engagement with the holder at the top of the tool.

The cam provided by my invention is indicated by the letter G and extends through the holder above the tool, preferably being held in an extension H of the holder formed near the end of the latter. The 70 holder is bored with a circular groove I which constitutes a bearing face for the circular portion of the cam while the projecting end J of the cam overlies the top of the groove B and is preferably of spiral 75 shape, its face gradually extending from the center so as to clamp tools of slightly varying widths.

The cam as thus far described is adapted to press the tool downward in its groove so 80 that its lower edge is in firm engagement with the undercut C, the tool being thus held against tilting. In the present construction the cam has an additional function, namely, that of preventing the sidewise movement of the tool out of the groove. To this end the cam is provided with an oblique or beveled face which is preferably of the same angle as the upper bevel edge E of the tool, so that 85 when the latter is clamped down it cannot escape sidewise. In the operation of clamping and particularly after the tool is clamped and the sidewise thrust occurs, there is a tendency to force or draw the cam through the holder, and to adequately hold the cam against this movement I pro-

- vide a shoulder K which bears against a similar shoulder L formed on the holder, the shoulder L being preferably formed at the bottom of an enlargement I' of the bore I as shown. The shoulder K is preferably formed as a flange lying wholly within the enlargement I', and the latter is preferably provided with an internal groove in which fits a spring ring M which bears against the flange and prevents the displacement of the cam in a direction away from the tool side of the holder. A wrench face such as the hexagon nut O is also provided for turning the cam.
- 10 It will be observed that the cam is adapted to engage side tools of various kinds such as cutting-off tools, side tools, etc. and that even if the tool is not provided with a beveled edge at its top it nevertheless is retained securely in position by the cam. It will also be observed that the holder is free from projecting parts on the tool side thereof so that it can be used close against the work.
- 15 25 It will be understood that while I have shown and described one form of the invention various changes can be made therein without departing from the spirit of the invention as set forth in the claims annexed.
- 30 What I claim is:—
1. A side tool holder or the like having a shallow groove in its side, and a rotatable cam at one side of said groove, said cam having a circular bearing portion, and a cam face projecting over said groove, said cam face having an undercut or bevel surface of substantially the width of said groove adapted to force the tool against the opposite side of the groove and hold the tool against sidewise displacement therein.
- 35 40 2. A side tool holder or the like having a shallow groove in its side, and a rotatable cam at one side of said groove said cam having a circular bearing portion, and a
- cam face projecting over said groove, said cam face having an undercut or bevel surface of substantially the width of said groove adapted to force the tool against the opposite side of the groove and hold the tool against sidewise displacement therein, 45 cam face projecting over said groove, said cam face having an undercut or bevel surface of substantially the width of said groove adapted to force the tool against the opposite side of the groove and hold the tool against sidewise displacement therein, 50 and said cam having a wrench face at the side opposite said cam face.
3. A side tool holder or the like having a shallow groove in its side, and a rotatable cam at one side of said groove said cam 55 having a circular bearing portion, and a cam face projecting over said groove, said cam face having an undercut or bevel surface of substantially the width of said groove adapted to force the tool against the 60 opposite side of the groove and hold the tool against sidewise displacement therein, and said cam having a shoulder bearing against said holder to prevent outward movement across the tool.
4. A side tool holder or the like having a shallow groove in its side, a circular bore leading to the top of said groove, and an enlargement of said bore on the opposite side to said groove, and a rotatable cam 70 having a circular bearing portion fitting said bore, a flange on one side thereof, in said enlargement, and a cam face on the opposite side of said bearing portion, projecting over said groove, said cam face having an undercut or bevel surface of substantially the width of said groove adapted to 75 force the tool against the opposite side of the groove and hold the tool against sidewise displacement therein.
- In witness whereof, I have hereunto signed my name in the presence of two 80 subscribing witnesses.

GEORGE AMBORN.
